UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING-MACHINE.

1,362,547.

Specification of Letters Patent. Patented Dec. 14, 1920.

Application filed August 12, 1919. Serial No. 316,981.

To all whom it may concern:

Be it known that I, JOHN WALDHEIM, a citizen of the United States, residing in Elizabeth, in the county of Union and State 5 of New Jersey, have invented certain new and useful Improvements in Typewriting-Machines, of which the following is a specification.

This invention relates to typewriting machines to be used for writing upon a number 10 of superposed sheets, especially webs or continuous sheets from which typed sections are intended to be torn off. Such webs are often made in the form of fan-fold webs 15 comprising a series of printed forms, each length of form adapted to be severed and removed when the typewriting thereon is completed. In such work it is desirable to employ carbon-sheets or the like interleaved 20 with the webs for making duplicate copies.

In the use of such carbon-sheets practical difficulties are encountered, especially in round-platen machines, in shifting the carbon-sheets from the portions of the webs 25 that have been written upon, back to new positions for writing upon the succeeding portions of the webs. These difficulties are due partly to the fact that the webs have to pursue a tortuous course in passing through 30 a round-platen machine, causing the carbons to be bound between the plies of web.

According to the present invention, the webs need not be entirely straightened, but the amount of their curvature in passing 35 around the platen may be reduced to a comparatively small arc so as to ease the webs at the time it is desired to shift the carbon-sheets. This arc may be made small enough to enable the carbon-sheets to slip readily 40 between the work-sheets, without displacing the platen. To obtain these and other advantages, I have contrived to introduce the horizontal webs in a front-strike typewriting machine, substantially at the bottom of 45 the platen, so that they curve forwardly up to the printing point, and for writing purposes may emerge rearwardly and upwardly from the platen.

When it is desired to shift the carbon-sheets relatively to the web, the web may be 50 opened out or nearly straightened. To permit this to be done, in the form herein illustrated, a paper-table or directrix above the

platen is adapted to be swung forward until the webs are cast off from the front of the 55 platen and stand at an inclination upwardly and forwardly from a point somewhat below or near the printing point, thus reducing the curvature of the webs to an arc of some 40° to 60°, this being sufficiently small to release the carbon-sheets from the grip of the 60 work-sheets and permit the carbons to be slid back to face fresh portions of the superposed webs.

To enable this swinging forward of the 65 webs to be easily accomplished, the paper-table aforesaid may be journaled preferably upon the platen axle, and, while turning from its normal writing position, may automatically cast off the usual feed-rolls. The 70 carbons may now be readily drawn rearwardly by any suitable device, such as the Underwood fan-fold machine carbon-paper carriage, one form of which is illustrated in the patent to Wernery & Smith, No. 75 1,132,055, of March 16, 1915.

Other features and advantages will herein-after appear.

In the accompanying drawings,

Figure 1 is a sectional side view of an Underwood standard typewriting machine modified to show one form of my invention as applied thereto.

Fig. 2 is a fragmentary perspective view of a carriage, showing the parts in writing 85 position.

Fig. 3 is a fragmentary sectional side view of the carriage and a type-guide, showing the parts positioned for withdrawing the carbon-sheets.

In the Underwood typewriting machine, keys 1, when depressed, carry down key-levers 2, causing sub-levers 3 to swing type-bars 4 upwardly and rearwardly against a platen 5, which is journaled by its axle 6 in 95 a shift-frame 7. Every time a type-bar 4 approaches the platen, a heel 8 upon it strikes a universal bar 9, to actuate the usual dogs 10 which control the carriage 11 by means of an escapement wheel 12; the connections including a pinion 13 connected to the escapement wheel and a rack-bar 14 connected to the carriage. The shift-frame 7 is supported in the carriage partly by arms 15 connected by a shaft 15a, and it also comprises a roll 16 running upon the shift-rail 105

17. Normally, the lower-case types 18 print through a ribbon (not shown) at the type-guide 19 upon the platen 5. When, however, a shift-key 20 is depressed, an arm 21 fast to the shift-key swings upwardly the frame 22, which includes the shift-rail 17, so that upper-case types 23 print instead of the lower-case types.

The carriage is supported upon a front rail 24, which may be of the usual sort, and is also supported upon a rear rail 25, which advantageously is located considerably lower than in the ordinary Underwood standard typewriting machine, so that webs 26, drawn over a rear paper-table 27, will be guided above the rail 25 and be directed to the platen at the usual rear feed-roll 28 at the front end of a substantially horizontal stretch of web.

20 As herein illustrated, the web 26 may be a fan-fold web, comprising three thicknesses for the sake of illustration, and between these are shown threaded carbon-sheets 29 which are held in any suitable manner to the clip bars 30 of a carbon-paper carriage 31, which may resemble, in many of its details, the usual Underwood fan-fold carbon-carriage. The carriage is shown as running upon rails 32, which form a rearward extension of the typewriter carriage, said extension being supported at its rear end by a roll 33 running upon a rail 34 forming a fixed extension 35 of the typewriter frame.

In order to guide the webs 26 to the carbon-carriage 31, they may be drawn over a rear bar 36 of the carriage provided with any usual or suitable form of edge gages (not shown). When the webs are introduced into the machine, they pass over the aforesaid paper-table 27 to the rear feed-roll 28 and then are guided upwardly by an apron 37, which may be carried on a rod 37^a fixed to the shift-frame, so that the webs pass between the front feed-rolls 38 and the platen 5, and then up in front of the platen past the type-guide 19 and the wing scales (not shown), and then onto a guide or directrix comprising a swing paper-table 39 above or at the delivery side of the platen.

50 The apron 37 may extend well up toward the printing line, so that a tangent drawn from its upper edges rises at an angle of about 60°.

The swing paper-table 39 is herein shown as provided with brackets 40 at its ends, said brackets being journaled by hubs 41 upon the platen axle 6, to permit the swing table to be swung forward from a stop 42, against which it normally rests, to the Fig. 3^a position, at which it is arrested by the stop 42 fast upon an end plate 43 of the shift-frame. The bracket 40 is provided with a tail 44 which arrests the swing table 39 by striking the stop pin 42 when the table reaches its proper position. When the table 39 is

swung forward to its Fig. 3 position, the angle of arc through which the webs 26 and the carbons 29 between them are turned is only about 60°, and it has been found that this arc on the ordinary Underwood standard platen is sufficiently small to allow the carbons to slip over the webs sufficiently readily for the purpose in hand. When the paper-table 39 is in the Fig. 3 position, the typist holds the leading ends of the webs 26 gaged against a suitable adjustable end gage 45 fast upon an upward extension or gage bar 46 of the table 39, and then pushes the carbon-paper carriage 31 rearwardly by means of its forwardly-extending handle 47. 70 75 80

There may be provided an adjustable stop 47^a for arresting the carriage 31 when the carbons 29 have reached any suitable point below the severing knife 48, which is fast to the table 39 and stands in front of it so that the webs and carbon-sheets are threaded between the knife and the table.

When the carbon-sheets have been brought behind the knife 48, the typist may swing the swing table 39 rearwardly to its Fig. 1 position, so that it will be caught in said position by means of the hook 49, which is adapted to catch over a pin 50 upon the swinging bracket 40 and hold the swing table 39 in its normal position. The webs may then be severed by drawing them against the knife, the webs usually being held sufficiently firmly by the feed-rolls 28 and 38. In order to enable the swing table 39 to be readily released from the hook 49, there is provided a handle 51 forming a bell-crank extension of the hook 49 and adapted to swing it on its pivot 52 against the tension of a spring 53, which normally holds it in effective position. A stop 54 holds the hook 49 in position to be 100 cammed upward by the pin 50 when the swing table 39 is swung backward.

In order to relieve the typist of the need of separately casting off the feed-rolls 28 and 38, and to insure that the parts are actuated in the right order, the swinging bracket 40 may be connected by a link 55 to a rock arm 56 fast upon the usual feed-roll casting-off shaft 57 of the Underwood shift frame, the connections being such that when the hook 49 holds the swing table 39 rearwardly the feed-rolls are effective, but when the swing table is in the Fig. 3 position the feed-rolls are automatically released.

To facilitate the guiding of the webs 26 across the paper-table 27 to the platen, there may be provided a paper shield 58, which lies above the paper-table 27, and, like it, is supported at each end by a bracket 59 fast in the typewriter carriage frame 11. To 120 prevent the accidental insertion of sheets above the paper shield 58, there may be provided a thin cross-plate 60 connecting the end plates 43 of the shift-frame 7, and extending downwardly far enough toward the 125 130

shield 58 to make sure that the typist will not accidentally slip the webs into the wrong opening.

It will be observed that the usual line-space wheel 61 of the Underwood standard typewriting machine may be fast to the platen axle, so that the usual line-space slide 62 may turn it when driven by the line-space handle 63. To facilitate entering the webs from the rear, both the paper-table 27 and the paper shield 58 may be provided with substantially deep curving rolls 64 to form a convenient guide for the paper.

To stiffen the paper-table 27, it may lie upon a bar 65 forming the stiff back of the frame of the carriage 11. To the posts 66 rising from the bar 65 are fast the brackets 67 which carry the rails 32, said rails being held together by connecting rods 68.

Variations may be resorted to within the scope of the invention, and portions of the improvements may be used without others.

Having thus described my invention, I claim:

1. In a front strike typewriting machine, the combination with a traveling carriage and a platen journaled therein, of a paper-table for introducing work-sheets from the rear substantially horizontally to a point near the bottom of the platen, a device normally supporting the sheets rearwardly above the platen at the front, a device for supporting work-sheets when stretched forwardly from the platen, and carbon-sheet-supporting means behind the platen adapted to withdraw from above the platen carbon-sheets interleaved between the work-sheets.

2. In a front strike typewriting machine, the combination with a traveling carriage and a platen journaled therein, of a paper-table for introducing work-sheets from the rear substantially horizontally to a point near the bottom of the platen, an axle for said platen, a second paper-table above the platen journaled on the axle, and adapted to be swung forward to carry the work-sheets tangentially away from the platen near the printing point, and an extension of the carriage behind the rear paper-table comprising carbon-sheet-supporting means adapted to withdraw carbon-sheets from between the work-sheets when the second paper-table is swung forward.

3. In a front strike typewriting machine, the combination with a traveling carriage and a platen journaled therein, of a paper-table for introducing work-sheets from the rear substantially horizontally to a point near the bottom of the platen, a rear rail for the carriage beneath the table, a second rail for the carriage, a support for the work-sheets when drawn forward to a position tangential to the platen near the printing

point, and a carbon-sheet-holder behind the rear rail adapted to withdraw interleaved carbon-sheets from between the work-sheets when the sheets lie in said tangential position upon the support.

4. In a front strike typewriting machine, the combination with a traveling carriage and a platen journaled therein, of a paper-table for introducing work-sheets from the rear substantially horizontally to a point near the bottom of the platen, an extension of said carriage behind the platen, a carbon-paper carriage running upon said extension, clips for holding carbons upon said carbon-paper carriage, and a paper support at the platen along which the work-sheets can be stretched sufficiently straight past the platen, to enable the carbon-paper carriage to shift the carbon-paper rearwardly of the work-sheets.

5. In a typewriting machine, the combination with a revoluble platen and feed rolls therefor, of a casting-off device for said rolls, a paper table adapted to be swung to reduce the arc a work-sheet is bent around the platen, and a connection whereby the swinging of the table casts off the feed-rolls.

6. In a typewriting machine, the combination with a revoluble platen and feed rolls therefor, of an apron adapted to guide work-sheets from beneath the platen to the printing point, an axle for said platen, a table above the platen adapted to swing on said axle to the front of the platen, upwardly and forwardly from the apron, a second paper-table adapted to guide work-sheets substantially to the bottom of the platen from the rear, and a carbon carriage adapted to be reciprocated behind the second table and to which carbon-sheets, interleaved between the work-sheets, are attached, said carbon carriage adapted to withdraw said carbon-sheets from the leading ends of the work-sheets, when the work-sheets extend upwardly and forwardly from the platen.

7. In a typewriting machine, the combination with a revoluble platen and feed-rolls therefor, of an apron adapted to guide work-sheets from beneath the platen to the printing point, an axle for said platen, a table above the platen adapted to swing on said axle to the front of the platen, upwardly and forwardly from the apron, a second paper-table adapted to guide work-sheets substantially to the bottom of the platen from the rear, a carbon carriage adapted to be reciprocated behind the second table and to which carbon-sheets, interleaved between the work-sheets, are attached, said carbon carriage adapted to withdraw said carbon-sheets from the leading ends of the work-sheets, when the work-sheets extend upwardly and forwardly from the platen.

the platen, and a casting-off device for said feed-rolls normally ineffective but made effective by the forward swinging of the first table.

8. In a typewriting machine, the combination with a revoluble platen and feed-rolls therefor, of an apron adapted to guide work-sheets from beneath the platen to the printing point, an axle for said platen, a table above the platen adapted to swing on said axle to the front of the platen, upwardly and forwardly from the apron, a second paper-table adapted to guide work-sheets substantially to the bottom of the platen from the rear, a carbon-carriage adapted to be reciprocated behind the second table and to which carbon-sheets, interleaved between the work-sheets, are attached, said carbon carriage adapted to withdraw said carbon-sheets from the leading ends of the work-sheets, when the work-sheets extend upwardly and forwardly from the platen, a hook normally holding said first paper-table in proper position, a finger piece adapted to be actuated to release the hook, and a stop for arresting the paper-table in its swung position.

9. In a front strike typewriting machine, the combination with a traveling carriage, of a revoluble platen therein, a paper-table behind the platen and substantially on a level with the bottom thereof, a rear rail for the carriage beneath said table, an extension of the carriage behind the table, a carbon-paper-carriage running on said extension, and a paper-holding device adapted to hold a straight stretch of work-sheets extending forwardly and upwardly from the platen to permit the carbon-paper-carriage to withdraw carbon-paper-sheets from between the work-sheets.

10. In a front strike typewriting machine, the combination with a traveling carriage, of a revoluble platen therein, a paper-table behind the platen substantially on a level with the bottom thereof, a rear rail for the carriage beneath said table, an extension of the carriage behind the table, a carbon-paper-carriage running on said extension, a paper-holding device adapted to hold a straight stretch of work-sheets extending forwardly and upwardly from the platen to permit the carbon-paper-carriage to withdraw carbon-paper-sheets from between the work-sheets, a shift frame in said traveling carriage in which the platen is journaled, and means for shifting said frame relatively to the paper-table.

11. In a front strike typewriting machine, the combination with a traveling carriage, of a revoluble platen therein, a paper-table behind the platen and substantially on a level with the bottom thereof, a rear rail for the carriage beneath said table, an ex-

tension of the carriage behind the table, a carbon-paper-carriage running on said extension, a paper-holding device adapted to hold a straight stretch of work-sheets extending forwardly and upwardly from the platen to permit the carbon-paper-carriage to withdraw carbon-paper-sheets from between the work-sheets, a shift frame in said carriage in which the platen is journaled, means for shifting said frame relatively to the paper-table, feed-rools mounted in said shift frame, adapted to hold work-sheets upon the platen, and a connection for automatically releasing said rolls by swinging the paper-holding device forward.

12. In a front strike typewriting machine, the combination with a traveling carriage, of a revoluble platen therein, a paper-table behind the platen and substantially on a level with the bottom thereof, a rear rail for the carriage beneath said table, an extension of the carriage behind the table, a carbon-paper-carriage running on said extension, a paper-holding device adapted to hold a straight stretch of work-sheets, extending forwardly and upwardly from the platen, to permit the carbon-paper-carriage to withdraw carbon-paper-sheets from between the work-sheets, a connection extending along the traveling carriage above the rear paper-table, and a paper shield adapted to guide forwardly and up around the platen work-sheets received from said table.

13. In a typewriting machine, the combination with a revoluble platen and feed-rolls therefor, of a casting-off device for said feed-rolls, a paper-table, an axle for the platen on which the paper-table is journaled, an extension of said table, and a connection from said extension to the casting-off device, and adapted to cast off the feed-rolls and strip the work-sheet from the printing line when the table is swung from its normal position.

14. In a typewriting machine, the combination with a revoluble platen and feed-rolls therefor, of a casting-off device for said feed-rolls, a paper-table, an axle for the platen on which the paper-table is journaled, an extension of said table, a connection from said extension to the casting-off device, and adapted to cast off the feed-rolls when the table is swung from its normal position, a shift frame comprising ends in which the platen is journaled and the feed-rolls supported, and a rear paper-table adapted to guide work-sheets to the feed-rolls.

15. In a typewriting machine, the combination with a revoluble platen and feed-rolls therefor, of a casting-off device for said feed-rolls, a paper-table, an axle for the platen on which the paper-table is journaled, an extension of said table, a connec-

- tion from said extension to the casting-off device, and adapted to cast off the feed-rolls when the table is swung from its normal position, a rear extension of the carriage 5 at the bottom of the platen, and a carbon-paper-carriage running upon said extension and adapted to withdraw carbons from between the work-sheets when the feed-rolls are cast off.
- 10 16. In a front strike typewriting machine, the combination with a revoluble platen, of a paper-table above the platen, a paper-table behind the platen adapted to deliver sheets nearly horizontally to the bottom of 15 the platen, a device normally holding the first paper-table, but adapted to permit it to be swung to carry the work-sheets upwardly and forwardly away from the platen to permit carbon sheets to be withdrawn 20 rearwardly therefrom, and a severing knife upon said first table, so that the sheets pass between it and the table.
17. In a front strike typewriting machine, the combination with a revoluble platen, of 25 a paper-table above the platen, a paper-table behind the platen adapted to deliver sheets nearly horizontally to the bottom of the platen, a device normally holding the first paper-table, but adapted to permit it to 30 be swung to carry the work-sheets upwardly and forwardly away from the platen, to permit carbon sheets to be withdrawn rearwardly therefrom, and a severing knife spaced from said first table, but connected 35 thereto to swing therewith, and adapted in the normal position of the table to permit work-sheets lying upon the table to be drawn against it to sever them.
18. In a front strike typewriting machine, 40 the combination with a traveling carriage and a platen revoluble therein, of a rear rail for the carriage, lower than the platen, an escapement for said carriage, also lower than the platen, a second rail for the carriage, a device for supporting work-sheets 45 to hold them substantially straight and extended upwardly and rearwardly from a position a little below the printing line, and a rear paper-table adapted to guide work-sheets above the rear rail and the escapement to the bottom of the platen.
19. In a front strike typewriting machine, 50 the combination with a traveling carriage and a platen revoluble therein, of a rear rail for the carriage, lower than the platen, an escapement for said carriage, also lower than the platen, a second rail for the carriage, a device for supporting work-sheets 55 to hold them substantially straight and extended upwardly and rearwardly from a position a little below the printing line, a rear paper-table adapted to guide work-sheets above the rear rail and the escapement to the bottom of the platen, said second paper-
- table fast in said carriage, and a shift-frame 65 forming part of the carriage in which said platen is journaled.
20. In a typewriting machine, the combination with a revoluble platen and feed-rolls therefor, of means to guide a pack of work-sheets and interleaved carbons substantially horizontally and tangentially to a point beneath the platen, a pivoted table above the platen, said table swingable forwardly to 70 reduce the arc of the work-sheets around the platen, so that the carbons may be readily shifted relatively to the work-sheets, and a connection from the table to separate the feed-rolls and said platen.
21. In a typewriting machine, the combination of a platen around which continuous webs and interleaved carbons may be passed, means for guiding the webs to the platen in a plane tangent to the platen, means for guiding the webs and carbons away from 75 the platen in another plane, the two planes being inclined toward each other and forming an angle of approximately 60° , a mounting for the second-mentioned means to permit it to be swung to increase the angle to 80 substantially 120° , and a carbon-carriage to shift the carbons relatively to the webs, said carbon-carriage being movable in a direction parallel to the first-mentioned plane.
22. In a typewriting machine, the combination of a platen around which continuous webs and interleaved carbons may be passed, means for guiding the webs to the platen in a plane tangent to the platen, means for guiding the webs and carbons away from 85 the platen in another plane, the two planes being inclined toward each other and forming an acute angle, a mounting for the second-mentioned means to permit it to be swung to increase the degree of the angle to 90 substantially 120° , and a carbon-carriage to shift the carbons relatively to the webs, said carbon-carriage being movable in a direction parallel to the first-mentioned plane.
23. In a typewriting machine, the combination of a platen around which continuous webs with interleaved carbons may be passed, to lie against the platen in an arc subtended by an angle in excess of 90° , means for guiding said webs and the carbons 95 to the platen in a plane tangent to the platen, a mounting, means to move the webs to decrease the arc around the platen, and a carbon-carriage to shift the carbons relatively to the webs, said carbon-carriage being movable in a direction parallel to the plane of approach of the webs to the platen.
24. In a typewriting machine, the combination of a revoluble platen, means for directing work-webs to the platen at the introductory side thereof, means for directing the webs away from the platen at the delivery side thereof, said introductory and

delivery directing means being relatively shiftable to ease the webs upon the platen while the latter is stationary, and means for shifting back interleaved carbons after the webs are eased.

25. In a typewriting machine, the combination with a revoluble platen and means at the introductory side of the platen for guiding webs thereto, of a carbon-shifter, 10 and a guide for the webs at the delivery side of the platen, said delivery guide being shiftable relatively to the platen to a position to ease the webs upon the platen and thereby relieve the pressure upon the interleaved 15 carbon, to permit the same to be drawn back by the carbon-shifter.

26. In a front-strike typewriting machine, the combination with a revoluble platen, of means at the introductory side of the platen, 20 for guiding work-webs forwardly about horizontally to the bottom of said platen, a carbon-carrier at the introductory side of the platen, and a work-guide at the delivery side of the platen, said work-guide normally 25 extending upwardly and rearwardly from the upper portion of the platen, and movable forwardly to partly cast off the webs from the front of the platen, thereby to ease the webs and permit the interleaved 30 carbon to be drawn back by the carbon-carrier.

27. In a front-strike typewriting machine, the combination of a revoluble platen, a substantially horizontal work-guide extending 35 forwardly to the bottom part of the platen, a carbon-shifter in rear of the platen, a guide at the delivery side of the platen for guiding webs back over the platen, said delivery guide being movable to cast off the 40 webs from the front of the platen to ease them sufficiently to permit the interleaved carbon to be drawn back by the carbon-shifter.

28. In a typewriting machine, the combination with a revoluble platen, of means 45 for guiding superposed plies of work-web with interleaved carbon around said platen and in contact therewith for a quarter of the circumference of the platen, said guiding means being shiftable relatively to the platen to cast off plies of web from a portion of the platen, to reduce the extent of contact of the web therewith to less than a quarter of the circumference.

55. 29. In a typewriting machine, the combination with a revoluble platen and means to guide work-webs with interleaved carbon to and around said platen and away therefrom, of feed-rolls to run upon the platen, 60 and means for casting off the feed-rolls and concomitantly casting off the webs from a portion of the platen while the latter remains stationary, to ease the webs sufficiently to permit the interleaved carbon to be drawn 65 back.

30. In a front-strike typewriting machine, the combination with a revoluble platen, of means to guide work-webs to and around the platen, whereby carbon interleaved between the webs is bound by said webs, a carbon-shifter, and means movable relatively to the platen to reduce the extent of the bend of the webs around the platen and thereby ease the webs sufficiently to permit the interleaved carbon to be drawn back relatively 75 to the webs by the carbon-shifter.

31. In a front-strike typewriting machine, the combination with a revoluble platen, of means to guide work-webs to and around the platen, whereby carbon interleaved between 80 the webs is bound by said webs, a carbon-shifter, means movable relatively to the platen to reduce the extent of the bend of the webs around the platen and thereby ease the webs sufficiently to permit the interleaved carbon to be drawn back relatively 85 to the webs by the carbon-shifter, a feed-roll for said platen, and means for releasing the feed-roll concomitantly with the easing of the webs.

32. In a front-strike typewriting machine, the combination with a carriage and a platen mounted thereon, of means connected with said carriage to lead a web from the rear of the carriage forwardly about horizontally 95 to the bottom of the platen, means above the printing line on the platen to direct the web rearwardly, said directing means movable to cast off the web from the front of the platen to ease the sheets, and a carbon-carrier for shifting the carbons rearwardly when the sheets are eased, said carbon-carrier mounted to move backwardly along the incoming web.

33. In a typewriting machine, the combination with a revoluble platen and means at the introductory side of the platen for guiding webs thereto, of a carbon-shifter, a guide for the webs at the delivery side of the platen, said delivery guide being shiftable relatively to the platen to a position to ease the webs upon the platen and thereby relieve the pressure upon the interleaved carbon, to permit the same to be drawn back by the carbon-shifter, and a gage on said 110 delivery guide for gaging the leading ends of the webs.

34. In a typewriting machine, the combination with a revoluble platen and means at the introductory side of the platen for guiding webs thereto, of a carbon-shifter, a guide for the webs at the delivery side of the platen, said delivery guide being shiftable relatively to the platen to a position to ease the webs upon the platen and thereby relieve the pressure upon the interleaved carbon, to permit the same to be drawn back by the carbon-shifter, and a web-severing device upon said delivery guide.

35. In a typewriting machine, the com- 130

bination with a revoluble platen and means at the introductory side of the platen for guiding webs thereto, of a carbon-shifter, a guide for the webs at the delivery side of 5 the platen, said delivery guide being shiftable relatively to the platen to a position to ease the webs upon the platen and thereby relieve the pressure upon the interleaved carbon, to permit the same to be drawn back by 10 the carbon-shifter, a gage on said delivery guide for gaging the leading ends of the webs, and a web-severing device upon said delivery guide.

36. In a front-strike typewriting machine, 15 the combination with a revoluble platen, of means at the introductory side of the platen for guiding work-webs forwardly about

horizontally to the bottom of said platen, a carbon-carrier at the introductory side of the platen, a work-guide at the delivery side 20 of the platen, said work-guide normally extending upwardly and rearwardly from the upper portion of the platen, and movable forwardly to partly cast off the webs from the front of the platen, thereby to ease the 25 webs and permit the interleaved carbon to be drawn back by the carbon-carrier, a gage on said delivery guide for gaging the leading ends of the webs, and web-severing means.

JOHN WALDHEIM.
